ARTIFICIAL LIMB,
APPLICATION FILED AUG. 10, 1918.

Patented Feb. 18, 1919.

2 SHEETS—SHEET 2.

UNITED STATES PATENT OFFICE.

ROBERT BRADLEY DICKSON, OF WEST POINT, MISSISSIPPI.

ARTIFICIAL LIMB.

1,294,632.

Specification of Letters Patent.

Patented Feb. 18, 1919.

Application filed August 10, 1918. Serial No. 249,362.

To all whom it may concern:

- Be it known that I, ROBERT BRADLEY DICKSON, a citizen of the United States, residing at West Point, in the county of Clay and 5 State of Mississippi, have invented certain new and useful Improvements in Artificial Limbs, of which the following is a specification, reference being had to the accompanying drawings.
- 10 This invention relates to artificial limbs, and has for one of its objects to provide an artificial leg, in the use of which the functions of the various parts of the natural leg are simulated in a life-like manner.
- 15 It is another object of my invention to provide an improved pneumatic cushion for the stump receiving socket of the limb, whereby friction upon the stump is obviated and it is cooled.
- 20 It is also one of the detail objects of the invention to provide improved means for operatively connecting the heel and toe portions of the foot to the shank of the limb.
- The invention likewise has for its object 25 to provide an artificial leg having a hollow shank and foot body formed of elastic material inclosing the mechanical parts of the device, and means for inflating the elastic body.
- 30 With the above and other objects in view, the invention consists in the improved construction, combination and relative arrangement of the several parts as will be herein-after more fully described, subsequently 35 claimed and illustrated in the accompanying drawings in which similar reference characters designate corresponding parts throughout the several views, and wherein:—

Figure 1 is a side elevation of my improved artificial limb illustrating one embodiment thereof;

Fig. 2 is a vertical longitudinal section;

Fig. 3 is a horizontal section taken on the line 3—3 of Fig. 2;

45 Fig. 4 is a section taken on the line 4—4 of Fig. 2; and

Fig. 5 is a detail perspective view of the ball joint member and the toe plate of the foot.

50 Referring in detail to the drawings, 5 designates the calf section, 6 the foot section, and 7 the thigh section of a continuous hollow wall constituting the body of the limb. The foot section may be provided with 55 separate toes of solid construction. This hollow body is preferably made up of lami-

nations of fabric and rubber adhesively secured together. I have illustrated in the drawings, a limb which is designed for use in those cases where the natural limb has 60 been amputated above the knee joint. It will, therefore, be understood that in those cases where the amputation has been made below the knee joint, the thigh portion 7 of the hollow body is, of course, eliminated and 65 the stump receiving socket, to be presently described, is secured within the upper end of the calf section 5 of said body.

A cylindrical shank 8 is vertically disposed within the hollow section 5 and at its 70 lower end is bored out to receive a bushing 9 having a flange or head 10 contacting with the lower end face of said shank. A rod 11, loosely engaged through said bushing, has a metal disk 12 fixed on its lower end. The 75 other end of this rod is threaded to receive adjusting nuts 13 which are housed within the end of the shank 8. A coil spring 14 is disposed upon said shank between the flange 10 and the disk 12 and acts to yieldingly 80 urge said disk downwardly and into engagement with the heel portion of the hollow body of the limb.

A steel plate 15 is engaged at one of its ends upon the bushing 9 and against the 85 lower end of the shank 8 and extends horizontally and forwardly from said shank. The forward end of this plate is fixed to a transverse bar 16 extending entirely across the foot at the ball thereof. A plate of resilient spring metal 17 is hinged to the bar 16, as shown at 18, and extends forwardly 90 into the toe portion of the foot 6. One end of a spring metal strap 19 is hingedly connected to the plate 17 at a point intermediate of its ends, as shown at 20. This strap 19 has its medial portion bent and disposed in parallel relation to the shank 8, as indicated at 21, and then again extended forwardly and hinged to the rear side of the bar 16, as at 22. Bolts 23 are fixed in the shank 8 in vertical, spaced relation to each other 100 and are loosely engaged through the medial portion 21 of the strap 19. Coil springs 24 are disposed upon said bolts between the strap 19 and the shank 8 and yieldingly retain said metal strap in spaced relation to the shank.

The shank 8 is formed with a threaded bore 25 opening into the upper end thereof 110 and in this bore a rod 26 is adjustably engaged. This rod is secured to or integrally

formed with the ball member 27 of the ball and socket knee joint. A nut 28 threaded upon said rod is adapted to be engaged with the upper end of the shank 8 to retain the 5 rod in its adjusted position.

29 designates the stump receiving socket, also having a threaded rod 30 fixed to its base for engagement in the interiorly threaded tubular shank 31 of the socket member 32 10 of the knee joint. This socket member at diametrically opposite points is pivoted or hinged to the ball member 27, as shown at 33. Preferably, the wall of the hollow body, within which the several parts are inclosed, 15 is heavily reinforced with fabric above and below the knee joint as shown at 34. A lock nut 35 is also threaded on the rod 30 to retain said rod in its adjusted position in the shank 31.

20 The stump receiving socket 29 is constructed of wood, and is provided with an outer peripheral rubber band 36 to which the upper edge of the thigh section 7 of the hollow body may be cemented. It is apparent, 25 however, that if desired various other means may be adopted for securely fastening the body of the limb to said socket member. The wall of this stump socket 29 is formed with a duct or passage 37 extending longitudinally through one side thereof and in the 30 upper end of this passage an air valve 38 is arranged. To the stem of said valve, a suitable inflating pump may be connected, whereby air under pressure may be supplied 35 through the passage 37 to the interior of the hollow body, whereby the collapse of the body walls under exterior pressure is effectually prevented.

The stump socket 29 is provided with an 40 interior sheet rubber wall 39 having a plurality of inwardly projecting air jet nipples 40. The wall of the socket member has a series of breather valves 41 therein to supply atmospheric air to the space between the 45 yieldable rubber wall 39 and the wall of the socket. These valves open inwardly. Thus, the pressure of the stump on the wall 39 against the air cushion between said wall and the wall of the socket, closes the valves 41 while the air is delivered inwardly in a 50 series of jets through the nipples 40 upon the stump. The yieldable wall 39 may be securely fixed in any preferred manner to the upper edge of the wall of the stump 55 socket 29. To the diametrically opposite sides of the socket 29, upwardly extending arms 42 are fixed, and to the upper ends of these arms, plates 43 are hingedly connected at one of their ends, as at 44. Each of these 60 plates is provided with a series of openings 45 to receive spaced studs 46 projecting from opposite sides of a split annular leather band 47. The spaced edges of this band may be connected together and the band tightly contracted on the thigh by 65

means of a suitable tape or string, indicated at 48.

From the foregoing description, taken in connection with the accompanying drawings, the construction, manner of operation 70 and use of the invention will be clearly and fully understood. By the provision of the resilient toe plate extending into the hollow toe portion of the foot section of the limb, and the resilient metal strap 19 connected to 75 the ball joint bar 16 and to said foot plate, the toe portion of the foot may flex or bend in a manner closely simulating the movement of the natural foot. By the adjustment of the nuts 13, the tension of the spring 14 may be properly regulated in accordance 80 with the weight of the person using the limb. By the provision of the pneumatic body within which the joint elements are housed or contained, I have succeeded in 85 greatly reducing the weight of such artificial limbs and by injecting air into the stump socket in the manner above explained, heating of the stump by friction is also obviated. Thus, the device may be worn with 90 a maximum of comfort. The device as a whole is also of relatively simple construction, not liable to get out of order, and capable of manufacture at comparatively 95 small cost.

While I have herein shown and described the preferred construction and arrangement of the several parts, it is to be understood that the device is susceptible of considerable modification therein and I, accordingly, reserve the privilege of adopting all such legitimate changes as may be fairly embodied within the spirit and scope of the invention as claimed.

I claim:

1. In an artificial limb, a hollow body including calf and foot sections having yieldable and inflatable walls, and jointed shank and foot members housed within the respective sections of the hollow body.

2. In an artificial limb, a shank, a horizontal plate fixed to the lower end of the shank and extending forwardly therefrom, a resilient foot plate hingedly connected to the forward end of said fixed plate, and a resiliently yieldable metal strap hingedly connected to the forward end of the fixed plate and to said foot plate respectively to yieldingly retain the latter in a normal position.

3. In an artificial limb, a shank, a horizontal plate fixed to the lower end of the shank and extending forwardly therefrom, a resilient foot plate hingedly connected to the forward end of said fixed plate, a resiliently yieldable metal strap hingedly connected to the forward end of the fixed plate and to said foot plate respectively to yieldingly retain the latter in a normal position, a bolt fixed in the shank upon which

said strap is loosely engaged, and a spring on said bolt urging the metal strap in one direction.

4. In an artificial limb, a shank, yieldable supporting means adjustably connected to the lower end of the shank, a bar constituting the ball of the foot rigidly connected to said shank in spaced relation thereto, a forwardly extending foot plate hinged to said bar, a resilient metal strap hingedly connected at one of its ends to the foot plate intermediate the ends thereof, the other end of said strap being hingedly connected to said bar, and means connecting the medial portion of said strap to the shank.

5. In an artificial limb, a stump receiving socket and means for supplying air to the interior of the socket including suction opened air valves mounted in the wall of the socket, and means arranged within the socket and yieldable under pressure of the

stump thereon to alternately draw air into the socket and force the same under pressure around the stump.

6. In an artificial limb, a stump receiving socket having a plurality of inwardly opening air valves in the wall thereof, a yieldable wall arranged within the socket in spaced relation to the wall thereof and having a plurality of inwardly projecting air jet nipples, the air in the space between said wall and the wall of the socket being forced under the pressure of the stump on said yieldable wall through the jet nipples and around the stump. 35

In testimony whereof I hereunto affix my signature in the presence of two witnesses.

R. BRADLEY DICKSON.
